UNITED STATES PATENT OFFICE.

AUSTEN M. CURTIS, OF EAST ORANGE, NEW JERSEY, ASSIGNOR TO WESTERN ELECTRIC COMPANY, INCORPORATED, OF NEW YORK, N. Y., A CORPORATION OF NEW YORK.

ISOCHRONIZING AND SYNCHRONIZING SYSTEM.

Application filed June 13, 1923. Serial No. 645,034.

To all whom it may concern:

Be it known that I, AUSTEN M. CURTIS, a citizen of the United States, residing at East Orange, in the county of Essex, State of New Jersey, have invented certain new and useful Improvements in Isochronizing and Synchronizing Systems, of which the following is a full, clear, concise, and exact description.

10 This invention relates to isochronizing and synchronizing systems and particularly to such systems for use with high speed multiplex telegraph systems.

In order to maintain synchronism between 15 the distributors at distant stations of a multiplex telegraph system, it is customary to take advantage of the fact that the rate of vibration of an electrically driven tuning fork which in turn drives the distributors, can be changed slightly by changing 20 its amplitude of vibration. A reduction in the amplitude of vibration of the fork results in an increase in the rate of vibration and conversely an increase in the amplitude 25 of vibration causes a reduction in the rate of vibration. The adjustment of the driving contacts also affects the degree of change in rate of vibration and it has been found that in some systems the rate of change of 30 frequency is not the same when the fork driving circuit is changed to decrease the frequency as when it is changed to increase the frequency of the tuning fork. Variations in frequency are also caused by variations in contact pressure and chattering of 35 the contacts, each of which changes the driving force. Although this irregularity in the frequency of vibration of the fork and its rate of change of frequency causes a 40 slight variation in phase between the distributors at the distant stations, it is not of sufficient magnitude to prevent satisfactory operation of the ordinary low speed multiplex telegraph system. However, in 45 high speed multiplex systems the distributors must be maintained in more exact synchronism in order to insure satisfactory operation. This has been found to be particularly true for systems used with long in- 50 ductively loaded submarine cables in which case economical use requires that the speed of transmission be raised to a value several times that of the ordinary multiplex system. The speed obtainable with a multiplex 55 system over such a cable may depend near-

ly as much on the exactness of synchronism maintained as it does on the characteristics of the cable.

The object of the present invention is to enable high speed synchronization to be obtained with more exact synchronism than has been possible heretofore, and a higher rate of change of frequency than in the systems used at present.

It is a further object in such systems to substantially reduce any difficulty due to 65 sparking at the contacts causing contact trouble and the radiation of high frequency waves and to maintain a constant speed of 70 operation.

To attain the main objects the invention contemplates a synchronizing system in which the tuning forks employed to drive the distributors at the stations are regeneratively driven and by the use of sharply 75 tuned electric circuits may be maintained at the desired frequency within very close limits. By changing the tuning of the driving circuit at the controlled station, the speed of vibration of the tuning fork at 80 that station is corrected when necessary so as to maintain very close synchronism between the distributors.

The various features of the invention may be more clearly understood by reference to 85 the accompanying drawings in which Fig. 1 shows a synchronizing system employing the features of the invention and Figs. 2, 3, 4 and 5 show various modifications of the tuning circuit disclosed in Fig. 1.

Referring more particularly to Fig. 1 the synchronizing equipment at station A which is the controlling station includes a phonic wheel 10, which is driven by electrical impulses from the grounded source of energy 95 11, alternately connected by means of the lower leg of the tuning fork 12 to the electromagnets 13—13 and 14—14. Mounted in close proximity to one leg of the tuning fork is a polarized electromagnet 15 in which 100 an alternating current is generated by the vibration of the fork. This electromagnet is connected to the primary winding of transformer 16, the secondary winding of which is connected to the input side of the 105 amplifier 17. The output side of this amplifier is connected to electromagnet 19, which is the driving magnet that keeps the fork in vibration, the current through electromagnet 19 being in proper phase re- 110

lation with respect to the movement of the fork. By means of the variable capacity 20, the variable inductance 21 and the variable resistance 22, the circuit including these 5 elements and electromagnet 15 is tuned to a frequency within the range of possible operation of the fork 12.

The phonic wheel 10 is employed to positively drive a rotatable brush arm 23 carrying 10 a plurality of insulated brushes 24, 25 and 26 which upon rotation of the switch arm are adapted to sweep over the distributor segments. The distributor, a portion of which is shown developed, consists of a set of receiving segments 27 which are successively connected to a receiving ring 28 by means of the brush 24, a set of correcting segments 29 which are successively connected to the correcting ring 30 by means of brush 25; and a 15 set of transmitting segments 31 which are successively connected to the transmitting ring 32 by means of the brush 26. The receiving segments are connected directly to the magnets 33-33 of the printing mechanism and the transmitting segments are connected to the contacts of the printing transmitter 34. The correcting segments, of which there are twice as many as of the transmitting or receiving segments, are used 20 only at the controlled station but are preferably included in the apparatus at each station so that, when desired, either station may be operated as the controlled station. The transmitting ring 32 is connected differentially to the line relay 35 and an artificial line is preferably provided, as shown, to permit duplex working over the system.

At station B which is the controlled station, the equipment is similar to that of 40 station A, except that additional means is provided for automatically varying the tuning of the oscillating circuit. The phonic wheel 10' is driven by the tuning fork 12' and the vibrations of the latter cause the 45 generation of an electromotive force in magnet 15' resulting in the flow of an electrical current in the tuned circuit 15', 21', 22', 16', 20' which is amplified and passed through magnet 19', thus maintaining the 50 tuning fork in vibration. The phonic wheel 10' is directly connected to the brush arm 23' which in its rotation causes brushes to sweep over a distributor consisting of receiving, correcting, and transmitting segments, similar to those of the distributor at 55 station A. The transmitting ring 32' is connected differentially to the winding of line relay 35' and the receiving ring 28' is connected to the upper contact of the line 60 relay. The correcting segments are divided into two sets of alternate segments which are connected respectively to the outer terminals of correcting relay 36. Assuming the direction of rotation of brush arm 23' to be from right to left, the correcting seg-

ments connected to the lower terminal of relay 36 are known as "slow" segments, while the alternate segments connected to the upper terminal of relay 36 are known as "fast" segments. The correcting common ring of the distributor is connected to the lower contact of the line relay through resistance 37 and condenser 38 connected in parallel and to the upper contact of line relay through resistance 39 and condenser 40 also connected in parallel. The armature of line relay 35' is connected to a 75 grounded source of energy 41 and the midpoint of the winding of correcting relay 36 is grounded. The operation of relay 36 80 serves to connect or disconnect the condenser 42 in parallel with condenser 20' in the driving circuit of the tuning fork and thus change the tuning of the circuit.

In the operation of the system the tuning forks at the respective stations are first set 85 in vibration by hand. Since the operation of these forks is similar, only that at station A will be considered. The vibration of the fork 12 generates an electromotive force in 90 the magnetized electromagnet 15 which produces an alternating current in the tuned circuit composed of the transformer 16, inductance 21, and condenser 20. By means of the transformer the voltage of this current is increased at the input terminals of the amplifier 17 which in turn produces a 95 large increase in the current flowing through the electromagnet 19. The phase relations between the current in the generating magnet 15 and the driving magnet 19 are such that the current generated tends 100 to maintain the vibration of the fork, which increases its amplitude of vibration to a point where the energy dissipated becomes 105 equal to the energizing force supplied, thus causing the fork to vibrate steadily at a given amplitude. The fork has a natural frequency of vibration which changes 110 slightly with amplitude, being slower for larger amplitudes and vice versa. If the circuit 15, 16, 20, 21, 22 is tuned by means of the inductance 21, resistance 22 and capacity 20 to a frequency within a certain 115 frequency range which corresponds to a certain portion of the amplitude range of the fork and the suitable degree of amplification provided, the fork will be maintained in vibration at a constant frequency and amplitude. The method of maintaining 120 the correct tuning of the circuit is as follows: Variable capacity 20 is disconnected and variable inductance 21 and variable resistance 22 are short circuited. The amplification is then increased until 125 the fork vibrates freely. The inductance and resistance elements 21 and 22, respectively, are then increased in value until the amplitude of vibration of the fork is materially reduced. The variable capacity 130

20 is next adjusted until the amplitude of vibration is increased to its maximum amount. If it is not possible to obtain the desired amplitude of vibration by adjustment of condenser 20, the value of inductance 21 should be decreased to a point where the desired amplitude of the vibration of the fork 12 is obtained. Assuming the fork to be vibrating at the amplitude set by the tuned circuit, it is obvious that any change in tuning will cause a change in the phase relation between the input and output of the driving system which must be accompanied by a change in frequency of the fork. 10

15

The vibration of the fork 12 causes the phonic wheel 10 to be rotated at a speed corresponding to the frequency of vibration of the fork, which is accomplished by means of current impulses from battery 11 alternately connected to electromagnets 13, 13 to 14, 14. The brush arm 23 is positively driven by the phonic wheel 10. Hence its speed of rotation is directly controlled by the vibration of the fork 12. 20

In the arrangement disclosed, station A is the controlling station, and the fork 12 is accordingly arranged to vibrate at a set speed. At station B, which is the controlled 30 station, the vibrating device is provided with a tuned operating circuit, which is capable of being altered by means of impulses received over the line from station A. Let it be assumed that station A is transmitting and the transmitter 34 is arranged to send a series of five positive or negative impulses over the line in accordance with well known systems employing the Baudot code. The brush 26, in its rotation, successively connects the segments 31 with ring 32 and current impulses are transmitted from transmitter 34 through line relay 35 over the line and through line relay 35' and thence through the artificial line to ground. Since 40 relay 35 is connected to the line differentially this relay is not operated by impulses sent from station A but relay 35' operates with each reversal of polarity of the impulses received. When the armature of relay 35' engages the contact 45, positive potential is applied from the battery 41 to the receiving ring 28' and thence by brush 24' to the segment 27' and the operating magnet 33' of the receiving mechanism. Since the present 45 invention relates to the method of driving the distributors in isochronism, further description of the receiving mechanism is unnecessary here except mention of the fact that the brushes at both stations must rotate in isochronism and in proper phase relation to insure correct reception of the transmitted signals. With the armature of relay 35' in the position shown a path is provided for current from battery 41 through contact 44, resistance 37 to correct- 50

ing ring 30' and thence through either a "fast" or "slow" segment 29 (depending upon the position of brush 25') and through either the lower or the upper winding of correcting relay 36 to ground. The resistance 37 (and also resistance 39) is of such a high value that the steady current flowing therethrough is insufficient to cause the operation of relay 36, and therefore no change is made in the operating circuit of fork 12'. The resistances 37 and 39 are provided for the sole purpose of providing discharge paths for condensers 38 and 40. Upon a change in the polarity of the signal received the relay 35' is operated in the opposite direction causing its armature to engage with contact 45, in which case a charging pulse flows from battery 41 through the armature and contact 45 of relay 35' through condenser 40 to correcting ring 30'. In case the distributor at station B is in exact synchronism with the impulses received from the distributor at station A, the brush 25' will be just passing from a fast segment 29' to a slow segment 29' or will be in contact with both segments. In either case the relay 36 will not be operated and the speed of rotation of the distributor at station B will not be altered. 80

If the distributor at station B is lagging, the brush 25' will join the correcting ring 30' with a slow segment 29' thereby completing the charging circuit for condenser 40 and the charging pulse passing through the lower winding of relay 36 will be of sufficient strength to cause the operation of the correcting relay. However, since this relay 36 is already operated in that direction, there will be no change in the tuning of the control circuit, which will remain as shown, the vibrating fork at station B, in accordance with a previous correcting pulse, continuing to increase in frequency, and causing the distributor B to gain on the distributor A. When the distributor B has gained sufficiently on distributor A to have advanced a little ahead of an isochronous position, a reversal of the line current will cause the armature of relay 35' to engage contact 45, and the charging impulse to come at a time when brush 25' is bridging correcting ring 30' and a fast segment 29', and it will therefore flow through the upper winding of correcting relay 36 causing this relay to operate and disconnect condenser 42 from the tuning circuit. Condenser 42 is assumed to be sufficiently large to place the resonant frequency of the tuned circuit outside of the range of possible fork frequencies. Upon disconnecting condenser 42 the speed of vibration will therefore begin to decrease as the voltage generated by the fork is increased by the tuned circuit, until a point is reached where the speed of vibration of the fork at station B and accordingly the phase 120

125

130

of distributor B is again lagging with relation to distributor A, in which case, upon reversal of relay 35', the correcting relay 36 will be operated to again connect the condenser 42 in parallel with condenser 20' of the tuning circuit.

In practice the operations occur in rapid succession and the receiving fork vibrates at a frequency intermediate the maximum and minimum values corresponding to the change in the tuning circuit which is not often allowed to remain fixed for a time sufficient to stabilize the rate of vibration of the fork at either extreme.

15 In the method described above the change of frequency of the fork is produced by detuning the tuned circuit by the addition of capacity but it is of course obvious that the same result could also be obtained by changing the other constants of the circuit.

Figs. 2 to 5 show various forms of tuned circuits which might be employed and which provide sharp tuning. In Fig. 2 the circuit shown is the same as the system shown in Fig. 1 consisting of the transformer 16 having a variable inductance 21 and variable resistance 22 in the primary circuit and a condenser 20 in parallel with the secondary circuit and the input terminals of the amplifier 17. In Fig. 3 the fixed inductance 50 is connected in series with the secondary winding of transformer 16 and the variable condenser 20 is connected across the input terminals of the amplifier. In Fig. 4 an auto-transformer 51 is employed with a fixed inductance 50 in series with the secondary winding and a condenser 20 across the input terminals of the amplifier 17. In Fig. 5 an auto-transformer 51 is employed and a resistance 52 and inductance 53 connected in series with the primary portion of the winding, while a variable condenser 20 is connected in parallel with the secondary portion of the winding which is connected directly across the input terminals of the amplifier 17. These modifications are shown to exemplify suitable circuits which may be sharply tuned but the invention is not limited to any particular tuning circuit since satisfactory operation may be obtained with any circuit which is sharply tuned.

What is claimed is:

1. An isochronizing system comprising a distributor for imparting impulses to a line, a vibrating mechanism for driving said distributor, a receiving distributor, a variable

vibrating mechanism therefor having a sharply tuned operating circuit, and means controlled by current impulses received from the transmitting distributor to vary the tuning of said operating circuit whereby the distributors are maintained in isochronism. 60

2. A synchronizing system comprising a distributor for imparting impulses to a line, a vibrating mechanism for driving said distributor, a receiving distributor, a variable vibrating mechanism therefor having a sharply tuned operating circuit, and means controlled by the line current reversals and cooperating with the receiving distributor 70 to automatically alter the tuning of said operating circuit whereby the distributors are maintained in synchronism.

3. In a synchronizing system, a distributor for imparting electrical impulses to a line, a second distributor for receiving said impulses, a vibrating mechanism having a sharply tuned operating circuit for driving said receiving distributor, and means for altering the tuning of said operating circuit 80 to vary the frequency of vibration of the vibrating mechanism.

4. In a synchronizing system, means for controlling the transmission of electrical impulses to a line, means for receiving said impulses, a vibrating mechanism having a sharply tuned operating circuit for driving said receiving means, and means for altering the tuning of the operating circuit to vary the frequency of vibration of the vibrating mechanism. 90

5. In a synchronizing system, a distributor for imparting electrical impulses to a line, a vibrating device for driving the distributor, a sharply tuned operating circuit 95 for operating the vibrating device at a predetermined frequency, a line relay operable by current impulses received over the line, a correcting relay, means dependent upon the operation of the line relay for imparting a 100 current impulse to cause the operation of the correcting relay, a second distributor for controlling the direction of operation of the correcting relay, a vibrating device for driving said second distributor, a sharply tuned 105 operating circuit therefor, and means under the control of the correcting relay for detuning said circuit.

In witness whereof, I hereunto subscribe my name this 7th day of June A. D., 1923.

AUSTEN M. CURTIS.
